UNITED STATES PATENT OFFICE.

MORRIS GERSH, OF NEWCASTLE, INDIANA.

DESIGN FOR A COMBINED SOAP AND GLASS HOLDER.

43,530.

Specification for Design.

Patented Feb. 11, 1913.

Application filed June 5, 1912. Serial No. 701,904. Term of patent 14 years.

To all whom it may concern:

Be it known that I, MORRIS GERSH, a subject of the Czar of Russia, residing at Newcastle, in the county of Henry and State of Indiana, have invented a new, original, and ornamental Design for a Combined Soap and Glass Holder, of which the following is a specification, reference being had to the accompanying drawing, forming part thereof.

The figure is a perspective view of a combined soap and glass holder, showing my new design.

I claim:

The ornamental design for a combined soap and glass holder, as shown.

MORRIS GERSH.

Witnesses:

LUIS FRED,

FRANK DONAHUE.
